CLAIM

The ornamental design for a combined gemstone and setting, as shown and described.

DESCRIPTION

FIG. 1 is a top plan view of a combined gemstone and setting showing my new design;

FIG. 2 is a front elevational view thereof;

FIG. 3 is a side elevational view thereof, the opposite side view being a mirror image;

FIG. 4 is a rear elevational view thereof;

FIG. 5 is a top, front, right side perspective view thereof;

FIG. 6 is another top plan view thereof;

FIG. 7 is another perspective view thereof; and,

FIG. 8 is a bottom plan view thereof.

The broken lines in FIGS. 6 and 7 are for purposes of illustration only and form no part of the claimed design.
